UNITED STATES PATENT OFFICE.

OTTO SCHUMANN, OF PHILADELPHIA, PENNSYLVANIA.

STREET-SWEEPING MACHINE.

SPECIFICATION forming part of Letters Patent No. 778,076, dated December 20, 1904.

Application filed March 22, 1904. Serial No. 199,345.

To all whom it may concern:

Be it known that I, OTTO SCHUMANN, a citizen of the United States, residing in the city and county of Philadelphia, State of Pennsylvania, have invented new and useful Improvements in Street-Sweeping Machines, of which the following is a specification.

My invention relates to a street-sweeping machine; and it consists of novel means for elevating the dirt, &c., and directing the same to a chute leading to a place of collection of said dirt, &c., a gate which may be placed in the path of the bucket, so as to receive the contents thereof, and then to be removed from said path to permit the unobstructed passage of said bucket, and other details of construction, as will be hereinafter set forth, the novel features being pointed out in the claims.

Figure 1 represents a top or plan view of a street-sweeping machine embodying my invention, certain parts of the frame of the machine having been removed. Fig. 2 represents a partial side elevation and partial vertical section thereof. Fig. 3 represents a side elevation of a detached portion, showing a certain member thereof in a different position from that shown in Fig. 2.

Similar letters of reference indicate corresponding parts in the figures.

Referring to the drawings, A designates the truck of the machine, to the sides of which are secured brackets B, on the lower ends of which latter is mounted the rotary brush C, which is adapted to direct dirt, &c., from the street into the primary receptacle D, which depends from the truck A and is firmly secured thereto and is in communication with the vertical casing E, which latter is supported on said truck and the cross-bar E^X thereon. On the shaft F of said brush is the sprocket-wheel G, around which passes the sprocket-chain H, the latter passing around the sprocket-wheel J on the counter-shaft K, which is mounted in hangers L on the truck A, said shaft K having also connected with it the spur-wheel M, which gears with the spur-wheel N, the latter being firmly secured to the axle P of the machine, said axle in the

present case being those of the hind wheels, it being evident that when the machine is in motion rotation is imparted to the wheel N and from thence to the wheel M, the sprocket-wheel J, the chain H, and the sprocket-wheel G, whereby the brush C is rotated, thus sweeping the dirt, &c., of the street into the receptacle D, as has been stated. The shaft K has sliding motions in the hangers L as its bearings, so that it may be moved to the right and left, and thereby place the wheels M and N in and out of gear, by which provision the power of the axle P is not communicated to the brush and elevator, and thus the latter remains inoperative. When, however, said shaft K is moved to the right, the wheels M and N are placed into gear, and rotation of the brush and elevator is thereby effected. In order to impart said sliding motions to the shaft K, I employ the elbow or elbow-arm Q, which has one limb freely engaging with said shaft K between collars Q' Q' thereon, and the other limb, R passing freely through the adjacent hanger L and is connected with the lever S, the latter being mounted on the truck A and connected with the rod T, the latter being attached to the lever U, which is mounted adjacent to the driver's seat, so that the driver can conveniently cause the operation of said shaft K in order to throw the brush C into and out of engagement with and from the axle P through the intermediate mechanism, as is evident.

On the shaft K is the sprocket-wheel V, around which passes the sprocket-chain W, the latter also passing around the sprocket-wheel X, which is mounted on the standards Y, which are supported within the receptacle D and casing E and furthermore held by the brace Y', which is connected with the frame of the machine. The shaft Z of said sprocket-wheel X also carries the sprocket-wheel A', around which passes the endless sprocket-chain B', the latter also passing around the sprocket-wheel C', mounted on the bottom of said standards Y. Connected with said sprocket-chain B' are the elevator-buckets D', which in their motions are adapted to enter 95 the receptacle D and then rise therefrom to

the top of the casing E, when they overturn and are adapted to discharge their contents into a chute E', which is connected with the upper portion of the casing E and the rear portion of the truck A and is in communication with the casing E by the opening F' on the rear side of the latter. In said opening F' is a gate G', which is adapted to be engaged by the elbow-lever H', which is mounted on the side of the casing E and adapted to have one limb, H³, engaged at intervals by the arm J', which is connected with and projects radially from the shaft Z, its other limb, H⁴, being adapted to engage with the under side of the gate G', so as to elevate the same, as shown in Fig. 2, it being noticed in Fig. 3 that the gate is adapted to lower, whereby the contents of the overturned elevator-buckets drop on said gate and are directed into the chute J', after which the gate is raised so as to permit the downward passage of said bucket without said gate affording an obstacle thereto. The rear of the chute E' opens into the chamber H² on the frame of the truck or machine, said chamber containing a box J', which is adapted to receive dirt, &c., as it leaves the chute E', it being made removable from said chamber H², so that the dirt, &c., deposited therein may be taken elsewhere.

30 The operation is as follows: The machine is advanced, and as the shaft K is rotated by the gearing employed motion is communicated to the wheel V, the chain W, and the wheel X, whereby as the buckets D' dip into the dirt, &c., deposited in the receptacle D by the brush C they convey their contents to the top of the casing E, when they overturn and dump said contents upon the gate G', the latter being in the position shown in Fig. 3.

40 Then as the arm J' engages the adjacent limb of the lever H' and depresses the same the other limb bears upwardly against the under side of the gate G' and lifts the latter to the position shown in Fig. 2, thus placing the same out of the path of the descending bucket. Then the arm J' clears the lever H', when the gate drops and is again projected below the next advancing bucket, as in Fig. 3, when said bucket is overturned and discharges its load upon said gate, thus directing the dirt, &c., into the chute E', as before, after which the lever H' is again engaged by the arm J', so as to elevate the gate, as in Fig. 2, and permit the descent of the last overturned bucket past the gate, as previously.

50 The machine is provided with the water-tank K' and sprinkling-pipes L', the former having therein the valve M', whose stem N' may be conveniently operated from the driver's seat.

60 The brush C extends obliquely across the truck of the machine and has one end extended beyond the rim of the adjacent wheel, so as to enter a gutter of a street or roadway,

and thus sweep the same, the dirt, &c., from said gutter then being directed into the receptacle D, which is also obliquely arranged so as to include the projected end of the brush in its compass, the sweeping of the gutter thus being sidewise, and hence made effective.

70 The hangers B are adapted to be lengthened and shortened to adapt the brush to be vertically adjusted.

Various changes may be made in the details of construction without departing from the general spirit of my invention, and I do not, therefore, desire to be limited in each case to the same.

Having thus described my invention, what I claim as new, and desire to secure by Letters Patent, is—

1. In a street-sweeping machine, a traveling bucket, a primary receptacle for the dirt, in which said bucket is movable, a rotary brush adjacent to the inlet of said receptacle, 85 a gate and means for moving said gate into and from the path of said bucket.

2. In a street-sweeping machine, a primary receptacle for dirt, &c., a bucket movable in said receptacle, a chute adjacent to said bucket 90 and a gate in said chute adapted to be placed in the path of said bucket to receive the contents thereof, and to be removed therefrom to permit the bucket to pass said gate.

3. In a street-sweeping machine, a bucket, 95 an endless conveyer therefor, a wheel for operating said conveyer, a bodily-slidable rotary shaft in the frame of the machine with which said wheel is geared, a rotary brush with which said shaft is geared, and means embodying an elbow-lever freely engaging said shaft and a pivoted elbow-lever and a slidable arm connected therewith, said lever freely engaging said shaft for imparting sliding motions to said shaft in its bearings. 100

4. In a street-sweeping machine, a bucket, an endless conveyer therefor, a wheel for operating said conveyer, a rotary shaft mounted for bodily endwise movement on the frame of the machine with which said wheel is 110 geared, a rotary brush with which said shaft is geared, and means for imparting sliding motions to said shaft in its bearings, said means consisting of a sliding arm which is freely connected with said shaft, an elbow-lever which is attached to said arm and a device under control of the driver for operating said lever in opposite directions. 115

5. In a street-sweeping machine, a conveyer, a bucket therein, a casing in which said conveyer and bucket are movable, a chute leading from said casing to a chamber on the machine, and a gate in said chute the same being adapted to be placed in the path of said bucket to receive the dirt, &c., and direct the latter 120 to said chute, said gate being also adapted to be moved from said path to permit the bucket to pass said gate. 125

6. In a street-sweeping machine, a receptacle for dirt, &c., a sweeping device adjacent to said receptacle, a traveling bucket adapted to enter said receptacle, means on the machine 5 for operating the traveler that carries said bucket, a gate mounted adjacent to said bucket and adapted to be placed into and out of the

path of the same, a lever adapted to engage with said gate and means adapted to engage with said lever to cause said gate to be raised.

OTTO SCHUMANN.
